UNITED STATES PATENT OFFICE.

SIMON C. LAUBER, OF TOLEDO, OHIO.

DESIGN FOR A TAG-FASTENER.

SPECIFICATION forming part of Design No. 29,062, dated July 19, 1898.

Application filed June 24, 1898. Serial No. 684,437. Term of patent 7 years.

To all whom it may concern:

Be it known that I, SIMON C. LAUBER, a citizen of the United States, residing at Toledo, in the county of Lucas and State of Ohio, have invented and produced a new and original Design for Tag-Fasteners, of which the following is a specification, reference being had to the accompanying drawings, forming part thereof.

10 Figure 1 is a side view of the tag-fastener. Fig. 2 is a plan view of the same.

The leading features of the design consist of the oval loop, one end of the loop being blunt and bent inward at the middle part of the loop on one side thereof and the other end of the loop being pointed and overlapping the blunt end, and the loop being bent in one direction only from its blunt end throughout its length, except at its pointed 20 end, which is bent outward and in the reverse direction.

The oval loop A constitutes the spring-wire

fastener, which engages with the tag. The blunt end *b* of the loop which is bent inward is arranged at the middle part of the loop on 25 one side thereof and will not penetrate the material to which the fastener is to be attached. The sharp-pointed end *c* of the loop constitutes the means for attaching the fastener to the material. The loop is bent in 30 one direction only throughout its length, except at its pointed end *c*, which is bent outward in the reverse direction and overlaps the end *b*.

What I claim is—

35 The design for a tag-fastener as herein shown and described.

In testimony whereof I affix my signature in presence of two witnesses.

SIMON C. LAUBER.
